[57] CLAIM

The ornamental design for a vehicle tire, as shown and described.

DESCRIPTION

FIG. 1 is a perspective view of a vehicle tire showing our new design, it being understood that the tread pattern is repeated throughout the circumference of the tire;

FIG. 2 is an end view thereof;

FIG. 3 is a side elevational view thereof, the opposite side being a mirror image thereof; and

FIG. 4 is a cross-sectional view thereof taken about line IV—IV of FIG. 2.

FIG. 1
